Primary Examiner — Barbara Fox*Assistant Examiner* — Harold E Blackwell, II(74) *Attorney, Agent, or Firm* — QuickPatents; Kevin Prince(57) **CLAIM**

The ornamental design for an acoustic tile installation tool, as shown and described.

DESCRIPTION

FIG. 1 is a top perspective view of an acoustic tile installation tool, showing my new design;

FIG. 2 is a bottom perspective view thereof;

FIG. 3 is a front elevational view thereof, the rear elevational view being a mirror image thereof;

FIG. 4 is a left-side elevational view thereof, the right-side elevational view being a mirror image thereof;

FIG. 5 is a top plan view thereof; and,

FIG. 6 is a bottom plan view thereof.

The broken lines in the figures depict portions of the acoustic tile installation tool that form no part of the claimed design.
